Primary Examiner—Bernard Ansher

Attorney, Agent, or Firm—James R. Duzan; Thomas R. Weaver

[57] **CLAIM**

The ornamental design for a high temperature, high pressure filter press for the testing of drilling fluids or similar apparatus, substantially as shown and described.

DESCRIPTION

FIG. 1 is a front perspective view of a high temperature, high pressure filter press for testing drilling fluids of my new design; and

FIG. 2 is a rear perspective view of a high temperature, high pressure filter press for testing drilling fluids of my new design.
